PROTECTIVE APPARATUS

Rolf Wideröe, Berlin-Karlshorst, Germany, assignee to General Electric Company, a corporation of New York

Application December 13, 1932, Serial No. 647,040
In Germany December 21, 1931

10 Claims. (Cl. 175—294)

My invention relates to improvements in protective apparatus and more particularly to improvements in fault responsive apparatus whose operation is so dependent on the function of the 5 current and the voltage of a circuit as to provide an action based on an impedance characteristic of the circuit.

The known reactance-dependent relays are similar to ohmmeters in design. Current and 10 voltage are applied to separate coils which exert a torque acting upon a movable system and causing it to operate when an impedance characteristic of a circuit differs from a predetermined value. Relays of this kind are comparatively complicated especially when a high degree of sensitivity 15 is required. One object of my invention is to cause reactance to act directly upon a relay which is of more simple construction.

My invention is based on the fact that the voltage of a circuit satisfies the equation

$$e = iR + L \frac{di}{dt}$$

Thus

$$e = L \frac{di}{dt}$$

at the moment the current passes through zero, that is, when $i=0$. The reactance is thus proportional to

$$e \frac{dt}{di}$$

when the current passes through zero. In the light of these facts, I provide a protective arrangement in which the condition of equilibrium of the releasing means is dependent upon two voltages one of which is proportional to the rate 35 of change of the power system current, that is,

$$\frac{di}{dt}$$

and the other proportional to the power system voltage, both of the voltages being active only approximately at the moment the current passes 45 through zero.

My invention will be better understood from the following description when considered in connection with the accompanying drawings, and its scope will be pointed out in the appended claims.

In the accompanying drawings, Figs. 1 and 2 50 are curve diagrams explanatory of my invention. Fig. 3 illustrates diagrammatically a protective arrangement embodying my invention; Figs. 4 and 5 illustrate modifications in parts of my in-

vention, and Fig. 6 illustrates another modification of my invention.

The diagram of Fig. 1 shows curves of the voltages which I employ in protective arrangements embodying my invention. The curve 10 represents

$$\frac{di}{dt}$$

that is the rate of change of current. The curve 11 represents the circuit voltage e . A third voltage represented by the curve 12 is dependent on the rectified circuit current. This third voltage which acts as an operation-preventing or device-locking voltage is added to the first two mentioned voltages. The purpose of this third voltage is to hold the device and to release it only when the third voltage is approximately zero. Thus, in the vicinity of zero, that is, substantially in the zone a , the release depends merely upon the relation between the voltages 10 and 11, that is upon

$$\frac{e}{\frac{di}{dt}}$$

80

or the reactance of the circuit under control. With the voltages as illustrated in Fig. 1, a response would occur at each zero point of the curve 12, since the bias of the voltage 12 then disappears, first in one sense and then in the other 85 with respect to the difference between the voltages 10 and 11. To avoid this, the curve 11 within the zone operating in the sense of release is either eliminated or reversed, as shown by the dashed line 13 in Fig. 1.

The algebraic sum of the instantaneous values of all the voltages may be applied to a polarized relay or to an electric discharge valve having a control electrode. An illustrative example embodying a discharge valve is shown in Fig. 3. An 95 alternating current circuit which includes conductors 14 and 15, and which is shown single-phase for the sake of simplicity, has connected thereto a current transformer 16 and a potential transformer 17. A resistance 18 and an inductance coil 19 are connected in the secondary circuit of the current transformer 16. Four suitable rectifiers 20, examples of which are well-known to the art, are connected across the resistance 18 for full-wave rectification. An impedance 21 is connected to these rectifiers. Consequently the voltage across the impedance is proportional to the rectified current in each half-wave as shown in curve 12 of Fig. 1. The voltage across the inductance coil 19 is pro- 100 105 110

portional to the circuit current and is phase displaced substantially 90° therefrom. In other words, it is proportional to the rate of change of the circuit current or

$$5 \quad \frac{di}{dt}$$

and is as shown by the curve 10 of Fig. 1. The voltage transformer 17 has two secondary windings 22 and 23. The voltage across the winding 22 is applied through a rectifier 24 to an impedance 25 so that the voltage across this impedance corresponds to the circuit voltage. This voltage may be indicated for a half cycle by the dashed line 13 in Fig. 1. If the algebraic sum of the instantaneous values of the voltages across the impedance devices 19, 21 and 25 is applied between the control electrode 26 and the cathode 27 of an electric discharge valve 28, and a bias battery 29 gives the valve a voltage which causes it to come into operation only when a voltage is produced in a given direction, that is when the circuit current is predominant, then the valve 28 comes into operation, that is it becomes conductive only when the reactance of the circuit 14, 15 is below a predetermined value.

In the embodiment of my invention shown in Fig. 3, the control electrode circuit has applied thereto a further voltage which is taken from the secondary winding 23 of the potential transformer 17. A resistance 30 in the circuit of the winding 23, an inductance coil 31, a rectifier 32 and an impedance 33 cooperate to render this voltage proportional to a rectified half wave of the circuit voltage. The arrangement is such that according to the direction of the flow of current which blocks the valve, the maximum value of this voltage coincides with the positive or negative maximum of the voltage acting to start the valve or render it conductive.

The influence of this voltage is shown by curve 9 of Fig. 2. In a certain position, the voltage 9 prevents the valve from being started, depending upon whether this voltage is produced at the moment the curve 12 passes through zero. Under the conditions illustrated in Fig. 2 the curve 9 is so positioned that it does not prevent the operation of the valve from being effected at the point a by the voltage 10. This operation is opposed merely by the value of the voltage 11. When, however, a change in the direction of the current relatively to the voltage causes the curve 9 to shift to such an extent that its voltage is active at the moment the curve 12 passes through zero, then it opposes the starting of the valve. Thus the reactance-operated arrangement is also caused to operate in dependence upon the direction of energy flow by the addition of the voltage 9, that is, the voltage across the impedance 33, as shown in Fig. 3. This directional feature is disclosed and claimed in my copending application, Serial No. 647,041, filed December 13, 1932, and assigned to the assignee of this invention.

To make zone a as small as possible, the slope of the curves 12 and 9 may be made as steep as possible. This can be obtained by selecting large amplitudes, that is the resistance 18 and the impedance 33 are chosen to provide high voltage drops. In order that the rectifiers 20 and the valve 28 may not be subjected to excessive voltages on the occurrence of faults within the protective zone, it is preferable that the crests of the curves 12 and 9 be flattened. This can be done by having the resistances 18 and 30 so voltage-dependent that their ohmic values decrease with

increasing voltage. Examples of such resistances are well known to the art, one suitable for the purpose being disclosed in United States Letters Patent 1,822,742, issued September 8, 1931.

As shown in Fig. 3, the releasing device to be operated by the anode current of the valve 28 is the trip coil 34 of a circuit breaker 35 arranged to control the circuit 14, 15. The characteristics of the trip coil may be such that the anode current of the valve is not sufficient to effect the operation of the trip coil directly as very sensitive discharge valves generally provide a small anode current. It is, therefore, suitable, as shown in Fig. 4, to have the valve 28 control another valve 36. For this purpose a resistance 37 is connected in series in the anode-cathode circuit of the valve 28 and one terminal of the resistance is connected to the control electrode of the valve 36. The anodes of both of the valves 28 and 36 are connected together and the cathode of the valve 36 is connected to the negative pole of the anode source. As soon as the valve 28 becomes conductive, the voltage drop across the resistance 37 reaches a value sufficient to cause the valve 36 to become conductive and the anode current supplied thereby is great enough to operate the trip coil 34.

In place of the valve 28 there may be connected to the auxiliary circuit conductors 38 and 39, as shown in Fig. 5, the operating winding 40 of a sensitive polarized relay 41, examples of which are well known to the art. The contacts 42 of this relay, as will be obvious to those skilled in the art, may be connected to control the circuit of the trip coil 34.

It is obvious from Figs. 1 and 2 that when only one half wave of the voltage 11 is rectified, there is always a discharge of the valve after one full cycle. When the discharge valve is of the ordinary type (for example a pure electron discharge valve), the current impulse produced at the end of each cycle furnishes for a short time an anode current through the releasing or tripping circuit. When the discharge valve is of the gas or vapor-filled type, a continuous anode current flows after one discharge but the discharge may often take place only after more than one-half wave following the occurrence of the fault. As shown in Fig. 6, shorter response times can be obtained by providing a second valve 43 upon the control electrode of which all the voltages act oppositely so that the response times of the two tubes have a relative time displacement of one-half wave. The voltages applied to the control electrode of the valve 28 as will be obvious from the figure are the same as those of Fig. 3 but the inductance coil 19 now takes the form of an insulating transformer 19' which is so connected to the impedance 21 as to obtain the necessary displacement at the control electrode of the valve 43. Similarly the rectifiers 24' and 32' are reversely connected to impedances 25' and 33' corresponding to the impedances 25 and 33. Obviously, in this arrangement the anode circuit may also be arranged as shown in Fig. 4, that is with an additional valve 36 capable of carrying high anode currents and allowing the use of highly sensitive valves 28 and 43.

While I have shown and described my invention in considerable detail, I do not desire to be limited to the exact arrangements shown but seek to cover by the appended claims all those modifications that fall within the true spirit and scope of my invention.

Letters Patent of the United States is:

Letters Patent of the United States

1. In combination with an alternating current electric circuit, means for deriving from said circuit a voltage dependent on the rate of change 5 of the circuit current, a voltage dependent on the circuit voltage, a voltage dependent on the rectification of both half waves of the circuit current and a voltage dependent on a rectified half wave 10 of the circuit voltage whose maximum value occurs substantially simultaneously with one of the maximum values of the voltage derived from the rate of change of circuit current and electro-responsive means connected to be energized in accordance with the algebraic sum of the instantaneous values of said derived voltages.

10 2. In combination with an alternating current electric circuit, means for deriving from said circuit a voltage dependent on the rate of change of the circuit current, a voltage dependent on a rectified half wave of the circuit voltage, a voltage dependent on the rectification of both half waves of the circuit current and a voltage dependent on a rectified half wave of the circuit voltage whose maximum value occurs substantially simultaneously with one of the maximum values of the voltage derived from the rate of change of circuit current and an electric discharge valve having a control electrode connected to be energized in accordance with the algebraic sum of the instantaneous values of said derived voltages.

30   3. In combination with an alternating current electric circuit, means for deriving from said circuit a voltage dependent on the rate of change of the circuit current, a voltage dependent on the circuit voltage, a voltage dependent on the rectification of both half waves of the circuit current and a voltage dependent on a rectified half wave of the circuit voltage whose maximum value occurs substantially simultaneously with one of the maximum values of the voltage derived from the rate of change of circuit current, electroresponsive means connected to be energized in accordance with the algebraic sum of the instantaneous values of said derived voltages and
35   40   45   45   cooperating electroresponsive means connected to be energized in accordance with the algebraic sum of the instantaneous values of voltages angularly displaced substantially 180° from said derived voltages.

50 4. In combination with an alternating current electric circuit, means for deriving from said circuit two voltages respectively dependent on the rate of change of the circuit current and on the circuit voltage, electroresponsive means connected to be energized for operation in accordance with the relation between said two voltages and means for permitting said voltages to become effectively operative to control said electroresponsive means only approximately at the moment the circuit current is passing through its zero value.

5. In combination with an alternating current electric circuit, means for deriving from said circuit two voltages respectively dependent on the rate of change of the circuit current and on the circuit voltage, electroresponsive means connected to be energized for operation in accordance with the balance between said two voltages, means for selecting a predetermined portion of the wave of one of said voltages to control the energization of said electroresponsive means and means for permitting said voltages to become effectively operative to control said electroresponsive means only approximately at the mo-

ment the circuit current is passing through its zero value.

6. In combination with an alternating current electric circuit, means for deriving from said circuit two voltages respectively dependent on the rate of change of the circuit current and on the circuit voltage, electroresponsive means connected to be energized for operation in accordance with the relation between said two voltages, means for rectifying a predetermined half wave of a voltage dependent on the circuit voltage to control the energization of said electroresponsive means and means for rectifying both half waves of a voltage dependent on the circuit current further to control the energization of said electroresponsive means.

7. In combination with an alternating current electric circuit, means for deriving from said circuit two voltages respectively dependent on the rate of change of the circuit current and on the circuit voltage, electroresponsive means connected to be energized for operation in accordance with a predetermined function of said voltages, means for rectifying a predetermined half wave of the voltage dependent on the circuit voltage to control the energization of said electroresponsive means, means for deriving a voltage dependent on the rectification of both half waves of a voltage dependent on the circuit current further to control the energization of said electroresponsive means and means for deriving a fourth voltage dependent on the rectified half wave of a voltage dependent on the circuit voltage whose maximum value occurs substantially simultaneously with one of the maximum values of the voltage derived from the rate of change of the circuit current still further to control the energization of said electroresponsive means. 95 100 105 110

8. In combination with an alternating current electric circuit, means for deriving from said circuit two voltages respectively dependent on the rate of change of the circuit current and on the circuit voltage, electroresponsive means connected to be energized for operation in accordance with a predetermined function of said voltages, means for rectifying a predetermined half wave of the voltage dependent on the circuit voltage to control the energization of said electroresponsive means, means for deriving voltage dependent on the rectification of both half waves of a voltage dependent on the circuit current further to control the energization of said electroresponsive means, means for deriving a fourth voltage dependent on the rectified half wave of a voltage dependent on the circuit voltage whose maximum value occurs substantially simultaneously with one of the maximum values of the voltage derived from the rate of change of the circuit current still further to control the energization of said electroresponsive means and means for flattening the crest of the wave of one of the last two mentioned derived voltages. 115 120 125 130 135

9. In combination with an alternating current electric circuit, means for deriving from said circuit two voltages respectively dependent on the rate of change of the circuit current and on the circuit voltage, electroresponsive means connected to be energized for operation in accordance with a predetermined function of said voltage, means for rectifying a predetermined half wave of voltage dependent on the circuit voltage to control the energization of said electroresponsive means, means for deriving a voltage dependent on rectification of both half waves of a voltage dependent on the circuit current further to con- 150

trol the energization of said electroresponsive means, means for deriving a fourth voltage dependent on the rectified half wave of a voltage dependent on the circuit voltage whose maximum value occurs substantially simultaneously with one of the maximum values of the voltage derived from the rate of change of the circuit current still further to control the energization of said electroresponsive means and means for flattening the crests of the waves of the last two mentioned voltages.

10. In combination with an alternating current electric circuit and circuit interrupting means

for controlling said circuit, means for deriving from said circuit two voltages respectively dependent on the rate of change of the circuit current and on the circuit voltage, electroresponsive means for controlling said circuit interrupting means in accordance with the balance between said two voltages and means for permitting said voltages to become effectively operative to control said electroresponsive means only approximately at the moment the circuit current is passing through its zero value.
